UNITED STATES PATENT OFFICE.

FRANK C. WATKINS, OF PHILADELPHIA, PENNSYLVANIA, ASSIGNOR, BY
MESNE ASSIGNMENTS, TO THE UNITED STATES KROTOPHONE COMPANY,
OF NEW YORK, N. Y.

KROTOPHONE.

SPECIFICATION forming part of Letters Patent No. 369,377, dated September 6, 1887.

Application filed November 15, 1886. Serial No. 218,957. (No model.)

To all whom it may concern:

Be it known that I, FRANK C. WATKINS, a citizen of the United States, residing at Philadelphia, in the county of Philadelphia and 5 State of Pennsylvania, have invented certain new and useful Improvements in Krotophones; and I do declare the following to be a full, clear, and exact description of the invention, such as will enable others skilled in the art to which it appertains to make and use the same, reference being had to the accompanying drawing, and to the letters and figures of reference marked thereon, which forms a part of this specification.

15 My invention has relation to certain new and useful improvements in the construction of krotophone-receivers, and the object is to provide a simple, reliable, and convenient form of receiver, whereby the voice will be reproduced

20 as received from the transmitter, thus avoiding all tendency to interruption from foreign influences, such as induced currents and other causes common to that class of receiving-instruments using a magnet or coil; and to 25 these ends the novelty consists in the peculiar construction and arrangement of the parts of the same, as will hereinafter be more fully described, and particularly pointed out in the claim.

30 The figure in the drawing is a longitudinal section of my improved krotophone-receiver.

The present invention is designed as an improvement in form upon the patent granted July 6, 1886, to Edward S. Spaulding, No. 345,084.

A is a rigid non-vibrating carbon diaphragm, provided with a central concave recess, *a*, and B is a metallic diaphragm mounted parallel with and separated from the diaphragm A by a flexible washer, *b*. 40

C is a carbon ball located in the recess *a* and forming a variable contact between the two diaphragms.

D is the case, and is provided with the usual ear-piece, E, and binding-posts *c e*, which are 45 respectively in connection with the two diaphragms. Through the medium of the flexible washer *b* the two diaphragms may be adjusted with reference to each other by tightening or loosening the ear-piece E. 50

For a complete description of the operation of the instrument, reference may be had to the patent to Spaulding, krotophone, granted July 6, 1886, No. 345,084.

Having thus described my invention, what 55 I claim is—

The combination, with the case D E, provided with the diaphragms or disks A B and carbon sphere C, of the flexible ring *b*, separating said diaphragms or disks, whereby they 60 may be adjusted with reference to each other as set forth.

In testimony whereof I affix my signature in presence of two witnesses.

FRANK C. WATKINS.
